Angelo Sapia, North Andover, Mass.

Application June 26, 1957, Serial No. 46,737

Term of patent 3½ years

(Cl. D58—26)

Fig. 1.

Fig. 2.

Fig. 3.

Fig. 1 is a side elevational view of a combined spout and closure cap, showing my new design;

Fig. 2 is a fragmentary rear elevational view thereof; and

Fig. 3 is a top plan view thereof.

The front and side not shown are substantially plain.

The essential features of my design reside in the portions shown in full lines.

I claim:

The ornamental design for a combined spout and closure cap, as shown and described.
